UNITED STATES PATENT OFFICE.

JACOB BUCHLI, OF WINTERTHUR, SWITZERLAND.

HIGH-PRESSURE STEAM BOILER FOR LOCOMOTIVES.

Application filed March 9, 1927, Serial No. 174,079, and in Germany April 14, 1926.

The present invention relates to improvements in high-pressure steam boilers for locomotives and particularly in fireboxes of such boilers.

5 In water-tube fireboxes of which a large number of types is known it is considered to be of principal importance that the tubes are simple to manufacture, that they form a tight obturation against the outside, that they may 10 be easily and rigidly connected and readily cleaned.

The subject matter of the present invention is a water-tube firebox comprising upper drums and lower drums, a front wall and a 15 rear wall, and tube elements connecting the upper drums to the lower drums and forming the roof and the lateral walls of the combustion chamber and consisting of several parts welded together to a fork shape.

20 In order to obtain the necessary direct heating surface in boilers of large output and yet to keep within the profile of the maximum fixed structure two upper drums must be used, so that the height of the firebox is not 25 too small and in order to provide for the necessary cross-section of the combustion chamber. The tube elements consist of three vertical tubes, each beaded into a lower drum. These vertical tubes form the lateral walls 30 of the firebox and an intermediate partition wall, and of the horizontal tube comprising two parts alternately connected to one of the two upper drums, the vertical and the horizontal parts of each element being connected with each other by means of three connecting pieces provided with openings for cleaning the tubes. The tube elements are thus 35 fork shaped having three prongs pointing in the downward direction whereby the horizontal parts of the element protect the upper drums in a known manner against the direct 40 action of the fire gases.

By this arrangement the required height of the firebox is obtained and the firebox may 45 be made wider than the frame of the locomotive if it is required in view of obtaining the necessary direct heating surface.

A constructional example of the subject matter of the present invention is illustrated 50 on the accompanying drawings, in which:

Fig. 1 is a longitudinal section through one of the combustion chambers and along line I—I in Fig. 2,

Fig. 2 is a cross-section of the firebox,

55 Fig. 3 shows on a larger scale the connection between a tube element and an upper

drum and the connection between a horizontal and a vertical part of a tube element,

Figs. 4 and 5 show in detail in a section and in a side view the cross-piece illustrated 60 in Fig. 3.

Referring now to the drawings the upper drums 1 and 2 are connected to the lower drums 3, 4 and 5 by means of the fork shaped tube elements 6 having three prongs. In the 65 front and at the rear the firebox is closed by the walls 7 and 8 respectively. In the lower part of the firebox the grate 9 is arranged. The vertical parts (prongs) 10, 11 and 12 of the tube elements are beaded into the re- 70 spective lower drums 3, 4 and 5 and are connected to each other and to one or the other of the upper drums by the horizontal part 13. The connection between the vertical and the horizontal parts of the tube elements is 75 effected by means of cross-pieces 14 and 15 which permit the beading and an easy cleaning. The tubes 11 beaded into the intermediate lower drum 4 divide the combustion space 80 into the symmetrical halves, each of which is provided with a separate fire-door 16 or 17 respectively.

In Figs. 3-5 the connection between the horizontal part 13 and the vertical part 10 of a tube element 6 by means of a cross-piece 85 14 is shown in detail. The branches 18 and 19 to be connected to the tubes 13 and 10 are provided with screw thread in order to obtain a rigid connection between branches and tubes and the ends of the tubes screwed to 90 the branches are welded to the latter at 20 and 21 respectively in order to obtain a steam tight connection. The other two branches 22 and 23 which are provided for cleaning purposes are closed by screw caps 24 which press 95 a packing ring 26 against the end of the branch through the intermediary of an insertion piece 25.

Fig. 2 shows the manner in which the firebox reaches beyond the frame 26 of the locomotive, 27 is the ash-pit.

I claim:

1. A locomotive boiler, comprising in combination, a pair of upper drums, lower drums, and a firebox comprising a front wall, a rear wall, and a plurality of fork shaped water tube elements arranged close together longitudinally of the locomotive boiler and forming the lateral walls and the roof of the firebox to protect the upper drums and an intermediate wall inside the latter, said fork shaped tube elements consisting of three 105 110

vertical tubes beaded into the lower drums and of a horizontal tube connecting said vertical tubes together, the horizontal tube of each tube element being provided with a single 5 vertical branch and said branches being alternately beaded into said upper drums.

2. A locomotive boiler, comprising in combination, two upper drums, three lower drums, and a fire box comprising a front 10 wall, a rear wall, and a plurality of fork shaped water tube elements closely arranged one behind the other in the longitudinal direction of the locomotive boiler and forming the lateral walls and the roof of the firebox, 15 said roof protecting the upper drums and an intermediate wall inside the latter, said fork shaped tube elements consisting of three vertical tubes beaded into the three lower drums and of a horizontal tube connected to 20 the upper ends of said vertical tubes by means of cross pieces to the sockets of which said tubes are screwed as well as welded, the remaining sockets being closed by screw caps for permitting a convenient cleaning of the 25 tubes, and the horizontal tube of each tube element being provided with a vertical branch

and these branches of the elements being alternately beaded into said two upper drums.

3. A locomotive boiler, comprising in combination, upper drums, three lower drums, 30 and a fire box comprising a front wall, a rear wall and a plurality of water tube elements arranged one beside the other in the longitudinal direction of the locomotive and each consisting of three vertical tubular parts 35 beaded at their lower ends into the lower drums and with their upper ends connected to a horizontal part arranged below and connected to said upper drums and forming the roof of the fire-box and protecting the upper 40 drums against the action of the fire gases.

4. In a high pressure locomotive boiler, a fork-shaped water tube unit comprising a transverse upper water tube and three water tubes extending downwardly therefrom, said 45 transverse tube having a removable closure at each end for the through passage of a cleansing tool, and the vertical tubes having removable closures at their upper ends.

In testimony whereof, I have signed my 50 name to this specification.

JACOB BUCHLI.
